CHARLES W. KEMPER AND JOHN T. KEMPER, OF ALAMEDA, CALIFORNIA.

CABLE CLAMP.

1,410,759.

Specification of Letters Patent. Patented Mar. 28, 1922.

Application filed November 3, 1920. Serial No. 421,440.

To all whom it may concern:

Be it known that we, CHARLES W. KEMPER and JOHN T. KEMPER, citizens of the United States, residing at Alameda, in the county 5 of Alameda and State of California, have invented new and useful Improvements in Cable Clamps, of which the following is a specification.

This invention relates to a cable clamp and 10 especially to improvements on the structure shown in our Patent No. 1,366,007, dated January 18, 1921, application for which was filed June 17, 1919.

One of the objects of the present invention 15 is to provide a simple, substantial cable clamp whereby cable ends may be effectively secured and prevented from accidentally separating when subjected to heavy strains or pulls, and especially to provide what may 20 be termed a unit clamp, that is a clamp which does not require bolts, nuts, etc., when in use and which does not employ any detachable or removable parts.

Another object of the invention is to provide 25 a cable clamp which functions like a wedge and which employs jamming rollers to secure the cable ends; further a clamp which is self locking and automatically increases its clamping action in proportion to 30 the pull exerted.

Another object of the invention is to provide means for securing the rollers against 35 removal when the clamp is not in use; also to provide means for securing the rollers against releasing or retrograde movement when in jamming position; further to retain the rollers elevated at all times, or in a position where they will not interfere with the free insertion or removal of the cable ends.

40 Other objects will hereinafter appear.

The invention consists of the parts and the construction, combination and arrangement of parts as hereinafter more fully described and claimed, having reference to the 45 accompanying drawings, in which—

Fig. 1 is a side elevation partially in section showing the clamp in position on a cable.

Fig. 2 is a cross section on line 2—2, Fig. 1. 50 Fig. 3 is a longitudinal plan section on line 3—3, Fig. 1.

Fig. 4 is a perspective view of the roller lock.

Referring to the drawings in detail, A 55 indicates in general the clamp forming the subject matter of the present application.

The clamps consist of a pair of side walls 2 and 3, which are tied together by a top section B and a bottom section C. Formed between the top and bottom sections and the 60 side sections 2 and 3, is a pair of chambers 4 and 5, which are triangular in shape and communicate with each other through means of a central chamber or passage 6. The apexes of the triangular shaped chambers 65 extend toward each other and terminate in the longitudinal central chamber 6. The upper section B consists of a horizontal portion 7 and an inclined portion 8. This inclined portion forms an acute angle with 70 relation to the cable ends 9 and 10, passing through the clamp, and is provided for the reception of a roller 11. The lower section C is similar to the upper section B as it also consists of a horizontal section, as indicated 75 at 7^a, and an angular inclined section 8^a which also forms an acute angle with relation to the cables. The inclined inner faces formed by the sections 8 and 8^a are parallel as are also the inner horizontal faces formed 80 by the sections 7 and 7^a.

There are two rollers employed, the one indicated as 11, and a second as 11^a. The opposite ends of the clamp are open, or in other words it may be stated that triangular shaped pockets terminate in openings through the respective ends of the clamp to permit free insertion of the rollers 11 and 11^a. These rollers are constructed substantially as shown in Figs. 1, 2 and 3. Their 90 faces are slightly concaved as at 12 to conform to the contour of the cables and each roller is provided with a central pin 14, the ends of which extend slightly beyond the parallel faces of the rollers. The rollers 95 are free to move longitudinally in the triangular chambers in the space formed between the side walls 2 and 3, as the width of the respective rollers is slightly less than the width of the chambers 4 and 5. Formed 100 in each side wall is a channel 15. These channels are provided for the reception of the projecting pin ends 14, and they serve the function of guiding the respective rollers when these are moved longitudinally within 105 the respective chambers. The channels which extend in a diagonal direction are disposed on the same angle as the inner faces of the inclined sections 8 and 8^a and the face of the respective rollers will therefore engage said interior inclined faces when movement is transmitted to the same in a longi- 110

tudinal direction; the channels forming no other function but that of a guide and a support for the respective rollers.

To prevent weakening of the side walls 5 2 and 3, offset portions are formed in the side walls as indicated at 16, and the channels are formed therein. This is of importance as considerable strain is exerted by the rollers when in gripping engagement 10 with the respective cable ends. To prevent removal of the rollers with relation to the respective chambers, we provide a roller lock such as indicated in Figs. 1, 3 and 4. This lock is constructed of sheet metal and 15 consists of a clip substantially as shown in Fig. 4. The legs of the clip, indicated at 17, are inserted in the channels 15 and the ends are then bent over or clinched as indicated at 18. The head 19 of the clip locks 20 the clip against inward movement, while the clinched over portion 18 secures the clip against outward movement. The head of the clip, in this manner, forms a closure for the end of the channels 15, or in other 25 words a stop which prevents endwise removal of the rollers. The offset portions 16 are provided with a slot at one end, as indicated at 20. These slots permit clinching or bending of the inner ends of the 30 legs of the clip, as indicated at 18, and they also permit insertion of a split cotter pin such as shown at 21. The cotter pin normally assumes the position shown in Figs. 1 and 3 when the clamp is not in use so as 35 to hold the rollers elevated and in their outermost positions, but the cotter pins are removed when the clamp is applied to a cable as shown in Fig. 1, and they are replaced behind the rollers as will hereinafter 40 be described, to secure the rollers against being accidentally released when in clamping or jamming position.

In actual operation, employing a clamp such as shown in Fig. 1, if it is desired to 45 secure a pair of cable ends, it is accomplished by slipping the cable ends through the clamp as shown; the rollers 11 and 11^a being held in their outermost positions when the cable ends are inserted by means of a 50 cotter pin 21. The moment the cable ends are in position, cotter pins 21 are removed and any suitable tool is inserted through the respective ends of the clamps to drive the rollers forward into engagement with 55 the cables and the interior inclined faces 8 and 8^a. A wedge action is in this manner produced which causes the rollers to effectively grip the respective cables; the cable ends becoming jammed between the 60 horizontal faces 7 and 7^a and the respective rollers 11 and 11^a. When the rollers have been driven into position, it is desirable to again insert the cotter pins. They are in this instance inserted behind the 65 rollers and when so placed secure the rollers

in jamming position and prevent accidental release of the same, that is a cable such as here shown when serving as a guy line may be subjected to considerable vibration and varying strains, such strains might have a 70 tendency to release the rollers, but such release is of course prevented in this instance by the cotter pins.

The present clamp is an improvement over that shown in our copending application, previously referred to. In actual experience we found that considerable trouble was encountered when applying the clamp, first due to the fact that the rollers would have to be inserted after the clamp has 75 been applied; secondly no means were provided for securing the rollers when in jamming position; third, loss of the rollers by escaping through the ends would sometimes happen if one cable end was pulled free. 80 All of these features proved decidedly objectionable in actual practice, hence the improved structure here shown.

For instance, first, by forming a channel in each side wall and by providing a pin on 90 each roller, it is obvious that the rollers will always be held in an elevated position where they will not interfere with the free insertion or removal of the cable ends; secondly by providing the clips shown in Fig. 4, loss 95 of either roller will be prevented as they cannot escape through the open ends of the clamp; third, by slotting the channel portions, or the offset sections 16 forming the same, as indicated at 20, it is possible to 100 insert a cotter pin which will secure the rollers either in released position or in jamming position; the latter being decidedly advantageous as it positively prevents accidental release of either roller.

The pin shown at 14 may be formed integral with the respective rollers, or may be inserted therein. The face of the rollers should be preferably slightly corrugated to form a good gripping surface between the 110 inclined faces and the cables; the clamps proper may be constructed of malleable iron, steel or the like. Cored openings may be formed as at 22 to permit the insertion of a driving tool when it is desired to release the rollers. While other features of the invention are more or less specifically illustrated, we wish it understood that various changes in form and proportion may be resorted to within the scope of the appended claims, similarly that the materials and finish of the several parts employed may be such as the experience and judgment of the manufacturer may dictate or varying uses may demand.

Various changes may be made in our invention within the scope of the appended claims and some modifications thereof are disclosed in our two co-pending applications Serial No. 463,664 and Serial No. 463,665, 130

filed April 22, 1921, which applications are divisions of this application.

Having thus described our invention, what we claim and desire to secure by Letters Patent is—

1. A cable clamp comprising a casing having an opening therethrough through which cables may be passed, a cable engaging member movable in the opening, guides in the casing, and means on the cable engaging member co-operating with the guides whereby said member is guided.
2. A cable clamp comprising a casing having an opening therethrough through which cables may be passed, cable engaging rollers movable in the opening, a guideway in the casing for each of the rollers, and means on the rollers for engaging in the guideways for movably retaining the rollers and guiding them.
3. A cable clamp comprising a casing having an opening therethrough through which cables may be passed, cable engaging rollers movable in the opening, a diagonally extending guideway in the casing for each of the rollers, and means on the rollers for engaging in the guideways for movably retaining the rollers and guiding them.
4. A cable clamp comprising a casing having an opening therethrough through which cables may be passed, cable engaging rollers movable in the opening, a guideway in the casing comprising a channel on opposite sides of the casing having a portion thereof open and a portion thereof closed, means on the roller engaging in the channel for guiding the roller.
5. A cable clamp comprising a casing having an opening therethrough through which cables may be passed, cable engaging rollers movable in the opening, a guideway in the casing comprising a channel on opposite sides of the casing having a portion thereof open and a portion thereof closed, means on the roller engaging in the channel for guiding the roller, and means adapted to be inserted through the open portion of the channel for retaining the roller in or out of its cable engaging position.
6. A cable clamp comprising a casing having an opening therethrough through which cables may be passed, cable engaging rollers movable in the opening, a guideway in the casing comprising a channel on opposite sides of the casing having a portion thereof open and a portion thereof closed, means on the roller engaging in the channel for guiding the roller, and means for closing the openings in the casing to prevent removal of the rollers.
7. A cable clamp comprising interspaced side sections, and integral top and bottom sections, a pair of open ended longitudinally extending triangular shaped chambers formed between the side, top and bottom sections through which a pair of cable ends are adapted to be extended, the apexes of said triangular shaped chambers extending toward each other and terminating in a central communicating passage, a roller insertable in each triangular shaped chamber, a pair of guideways formed in the side sections of the clamp and at each end thereof, and means on each roller extending into said guideways.
8. A cable clamp comprising interspaced side sections, and integral top and bottom sections, a pair of open ended longitudinally extending triangular shaped chambers formed between the side, top and bottom sections through which a pair of cable ends are adapted to be extended, the apexes of said triangular shaped chambers extending toward each other and terminating in a central communicating passage, a roller insertable in each triangular shaped chamber, a pair of guideways formed in the side sections of the clamp and at each end thereof, and a pin in each roller extending into said guideways.
9. A cable clamp comprising interspaced side sections, and integral top and bottom sections, a pair of open ended longitudinally extending triangular shaped chambers formed between the side, top and bottom sections through which a pair of cable ends are adapted to be extended, the apexes of said triangular shaped chambers extending toward each other and terminating in a central communicating passage, a roller insertable in each triangular shaped chamber, a pair of guideways formed in the side sections of the clamp and at each end thereof, a pin in each roller extending into said guideways, and a stop member at the end of each guideway to prevent endwise removal of the rollers.
